UNITED STATES PATENT OFFICE

2,358,012

LIQUID FUEL BURNER

Bertrand B. Kahn, Cincinnati, Ohio, assignor to
The Estate Stove Company, Hamilton, Ohio, a
corporation of Ohio

Application May 26, 1941, Serial No. 395,277

5 Claims. (Cl. 158—91)

This invention relates to heating devices and burners therefor, and more particularly to oil burners and heating devices utilizing the same.

It is the principal object of the invention to provide an oil burner adapted to operate uniformly, efficiently, and without objectionable noise over a wide range of burning conditions and with regulated combustion from a low or stand-by rate up to the maximum rate for which the burner is designed.

It is a further object to provide such a burner in which a properly regulated operation continues notwithstanding the collection of a body of unburned fuel therein as may occur with a temporary reduction in the rate of burning, caused for example by the opening of the door of the heater or in some other manner reducing the draft conditions.

It is a further object to provide such a burner which will operate over the desired wide range of burning rates without objectionable production of noise or formation of carbon deposits upon the burner walls, and with high efficiency.

Other objects and advantages of the invention will be apparent from the following description, the accompanying drawing, and the appended claims.

In the drawing.

Fig. 1 is a view in section and partially in side elevation, showing a heater and burner arrangement constructed in accordance with the present invention;

Fig. 2 is a detailed horizontal sectional view through the burner above the pilot ring with portions of the burner wall broken away to more clearly show the construction.

Referring to the drawing which illustrates a preferred embodiment of the invention, there is shown a heater of the general type illustrated in co-pending Patent No. 2,252,182, issued August 12, 1941, and assigned to the same assignee as this application. As shown, this heater comprises a base member 10 suitably apertured as shown at 11 for the introduction and upflow of air to be heated. An outer casing 12 is supported upon the base and provided with lower louver openings 13. An access door 14 is mounted on the casing, and a top outlet grill 15 provides for egress of the heated air currents. Spaced from the outer casing 12 is an inner casing 20 having an access door 21 in alignment with and somewhat smaller than door 14 so that by opening both doors access may be secured to the interior of the inner casing 20. A flue 22 extends outwardly through the outer casing from the top of the inner casing 20 providing for venting the products of combustion.

A flange 24 projecting inwardly from the wall of casing 20 provides a support for the burner proper, indicated generally by numeral 25. The burner, or burner pot, consists of a bottom bowl 60

or pan 26 having imperforate side and bottom walls, and into which fuel is supplied from a fuel pipe 27, a suitable starting pad 26' formed of asbestos or the like being preferably positioned on the bottom of the pan 26 for facilitating the lighting of the burner in a cold condition when fuel is supplied thereto.

In order to provide for the proper operation of the burner at low rates of combustion, such as for stand-by conditions where a minimum rate of burning is desired, merely sufficient to maintain combustion, a pilot ring 30 is suitably supported within the lower combustion chamber 26. This pilot ring is preferably removably positioned within the burner and supported at approximately the level of the top of the bowl by suitable means such as a plurality of pins 31 projecting inwardly from the wall of the bowl and adapted to receive and support the ring thereon. Satisfactory results are attained with a ring formed with a horizontally extending annular portion adapted to closely approach the side wall of the bowl and to substantially close off communication around the periphery of the bowl, except through the apertures to be hereinafter described. At its central portion, the pilot ring is preferably formed with an upstanding neck 32 defining a central aperture of suitable size in relation to the spacing of the pilot ring above the bottom of the bowl to provide for transmission of the proper quantities of heat to the bottom of the bowl for vaporizing the freshly introduced fuel.

Above the bowl, the burner is provided with an upper combustion chamber 35 defined by a substantially cylindrical side wall 36 terminating in an upwardly and outwardly extending flange 37 which is received in supporting relation upon the flange 24, the burner thus being adapted to be readily assembled and removed from its operative position within the heater.

The side wall 36 of the burner defining the upper combustion chamber is provided with a plurality of perforations 40. These perforations include a lower uniformly distributed group 41 which are preferably given a downward inclination as illustrated in Fig. 1, preferably being formed with the axis of each such hole at approximately a 45° angle as shown, so that they tend to direct their air streams inwardly and downwardly. In order to provide for the supply of combustion air from above the ring into the lower combustion space, a series of apertures 42 is preferably provided in the periphery of the pilot ring in substantial register with the perforations 41, suitable indexing means such as pin 42a being provided for maintaining the ring in proper predetermined angular relation with respect to said perforations. Preferably the number of corresponding perforations 41 and apertures 42 are so limited that under stand-by

Il est à présent possible de déterminer la distribution de la densité de la population dans un territoire à l'aide de la méthode de la statistique des probabilités. La méthode consiste à déterminer la densité moyenne dans un territoire et à déterminer la variance de la densité dans ce territoire. La variance est une mesure de la dispersion de la densité dans le territoire. La variance est calculée en utilisant la formule suivante : $S^2 = \frac{1}{n} \sum (x_i - \bar{x})^2$ où x_i est la densité à la localité i , $\bar{x}$ est la densité moyenne et n est le nombre de localités dans le territoire.

apertures 42 formed in the pilot ring 30, the latter ring having an internal diameter of its aperture of approximately 4 to 5 inches. A similar number of apertures 40 (in this case 48 in number, each having a cross sectional area of .007543 square inch) was present in each of the several series thereof, while the number of air inlet apertures 45 was increased as required to supply the necessary oxygen for assuring proper combustion conditions under varying rates of operation. In the construction shown a total of 252 such apertures 45 was provided each having a cross sectional area of .007238 square inch. The depth of the portion 53 of the cover plate 50 was approximately $\frac{3}{4}$ of an inch below the level of the top of the cover plate, the diameter of the central aperture 54 of this plate being approximately $7\frac{3}{4}$ inches. With other burner sizes, corresponding and similarly proportioned constructions have been found to give highly satisfactory results.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a combustion device of the character described, a liquid fuel burner comprising a lower combustion chamber for receiving the liquid fuel and having an imperforate side wall, a pilot ring forming the top wall of said lower combustion chamber and having a centrally located aperture therein, an upper combustion chamber having a side wall with perforations therein providing lower and upper air inlets for the introduction of the air needed to complete combustion, a portion of said lower air inlet openings being formed to direct the air streams therefrom inwardly and downwardly to the space below said pilot ring, said pilot ring having peripherally located apertures providing for the passage of combustion air therebeneath, an upper cover plate having a central aperture overlying the top of said burner and spaced from said pilot ring above said upper air inlet apertures, said cover plate having a downwardly projecting flange thereon for baffling and limiting the flow of combustion air from said upper air inlet apertures.

2. In a combustion device of the character described, a liquid fuel burner comprising a lower combustion chamber for receiving the liquid fuel and having an imperforate side wall, a pilot ring forming the top wall of said lower combustion chamber and having a centrally located aperture therein, an upper combustion chamber having a side wall with perforations therein providing lower and upper air inlets through which the entire supply of combustion air is introduced, a portion of said lower air inlet openings being formed to direct the air streams therefrom inwardly and downwardly to the lower combustion chamber, said pilot ring having peripherally located apertures providing for the passage of combustion air therebeneath, an upper cover plate overlying the top of said burner and spaced from said pilot ring above the uppermost of said air inlet apertures, said cover plate having an outer annular portion adjacent the periphery of said combustion chamber and an inner portion

located centrally of said annular portion and depending in the path of the air streams from said upper air inlet apertures for baffling and limiting the flow of air from said upper air inlet apertures.

3. A burner for liquid fuel adapted for efficient and quiet operation at both low and high rates of combustion comprising a burner pot having a generally cylindrical wall the lower portion of which is imperforate, a pilot ring within said lower portion defining the top of a lower space and having a central aperture therein for the upward passage of the flame and heated gases therethrough, means for introducing liquid fuel into said lower space, said cylindrical wall above the level of said pilot ring having air inlet openings formed therein, a cover plate overlying and closing the top of said pot, said plate having a flat outer part adjacent said cylindrical wall and extending inwardly toward and normal to the axis thereof, said cover plate also having an inner downwardly inclined portion extending below the level of the uppermost of said air inlet apertures and leaving a central opening above and in substantial alignment with said central aperture in said pilot ring to provide direct upward flow of the flame and hot gases while avoiding interference from direct inward flow of air from the uppermost of said air inlet apertures providing freedom from disturbance of combustion and occurrence of segregation and striations in the upwardly flowing gases.

4. In a combustion device of the character described, a burner pot having air inlet openings distributed over and confined to the side wall thereof, means to introduce liquid fuel into the lower part of said pot to be vaporized, a cover on the top of said pot closing the side wall thereof above said air inlet openings, said cover extending a substantial distance radially inwardly at the top of said pot above the level of said air inlet openings to provide for the supply of air inwardly through said openings in a substantially radial direction, said cover also having an inner portion depending downwardly to approximately the level of the upper of said air inlet openings and defining a central opening for the upward passage of the combustible mixture substantially free of objectionable segregation and striations.

5. In a combustion device of the character described, a burner pot having a lower imperforate wall portion and having air inlet openings distributed over and confined to the side wall of said pot above said lower imperforate portion, means to introduce liquid fuel into the lower imperforate part of said pot to be vaporized, a pilot ring positioned above the bottom wall of said pot and within the imperforate portion thereof and having a central opening, a cover on the top of said pot closing the side wall thereof above said air inlet openings, said cover extending a substantial distance radially inwardly at the top of said pot above the level of said air inlet openings to provide for the supply of air inwardly through said openings in a substantially radial direction, said cover also having an inner portion depending downwardly to approximately the level of the upper of said air inlet openings and defining a central opening for the upward passage of the combustible mixture substantially free of objectionable segregation and striations.

BERTRAND B. KAHN.
